ATTY.

UNITED STATES PATENT OFFICE.

EARLE G. WINSTON, OF PITTSFIELD, MASSACHUSETTS, ASSIGNOR TO GENERAL ELECTRIC COMPANY, A CORPORATION OF NEW YORK.

TRANSFORMER-TERMINAL.

1,022,912.

Specification of Letters Patent.

Patented Apr. 9, 1912.

Application filed May 28, 1909. Serial No. 498,917.

To all whom it may concern:

Be it known that I, EARLE G. WINSTON, a citizen of the United States, residing at Pittsfield, county of Berkshire, State of Massachusetts, have invented certain new and useful Improvements in Transformer-Terminals, of which the following is a specification.

My invention relates to the terminal connections for electrical apparatus, and has for an object an improvement in such connections whereby they may be made conveniently and cheaply.

In electrical apparatus, where it may be desired to vary the voltage by varying the number of units in series with the circuit, and especially transformers which have a winding and a number of taps connected to the winding, in order that the voltage may be varied in the manner well understood by those skilled in the art, it has been the custom in the past to connect the several taps to special end-connections independent and insulated from each other, and when it is desired to change a conductor leading to such apparatus from one tap to another, it has been necessary to do this in a somewhat cumbersome manner. This is what I seek to avoid by my invention, and I accomplish its object by the employment of a special form of compound terminal which may extend through the casing of the apparatus, and consists broadly of a plurality of substantially parallel conductors separated from and fastened to each other by the insulating material, so as to form a unit. The ends of these conductors inside the casing are connected each to a tap on the winding, and the ends outside the conductors are connected each to a substantially disk-shaped conducting member, these members being arranged coaxially with the unit and insulated from each other. In addition to the terminal, I employ a special form of connector arranged so that it may be quickly attached to or detached from the several disks, so that it may readily be connected to the desired tap of the winding.

For a further understanding of my invention, reference may be had to the accompanying drawing, where—

Figure 1 represents an external view of a transformer or other electrical apparatus provided with my new invention; Fig. 2 represents a section of a terminal on a larger

scale; Fig. 3 represents details of the terminal; and Figs. 4 and 5 are a section and side view, respectively, of the connectors which are used.

Referring first to Fig. 1, I have shown an electrical apparatus 1 containing windings which are not shown, to one end of which windings are connected terminals 3, which may be of any of the well known forms, and to the other ends of which are connected my new terminals 2.

Referring now to Fig. 2, 3¹ is a central conducting member or rod, to the upper end of which is attached a substantially disk-like conducting member 4. Around the edge of this member is a groove 5. Surrounding the rod 3 is an insulation 6. Surrounding these are two rings 7 and 9, which are shown as substantially similar in size and positioned adjacent to the ends of rod 3. Connecting these two rings is a conductor 8, which will be substantially parallel to rod 3. Attached to disk 9 is a disk 4¹, similar to disk 4, and insulated therefrom by insulating material 10.

The terminal may be built up of a number of members similar to 8, but for purposes of illustration, I have shown a terminal composed of two such members only. Insulating member 11 surrounds member 8 and insulation 6, and surrounding 11 are two rings 12 and 13, similar to rings 7 and 9, but of a larger diameter connected together by conductor 14. Ring 13 is attached to a disk-like conducting member 4² similar to disk 4¹ and insulated from it by an insulating member 15. Insulating member 16 surrounds 14 and insulating member 11. The several insulating members may be so constructed as to fasten the several conductors together and thus build up the terminal so as to form a convenient whole or unit. I have shown diagrammatically a source of voltage such as transformer windings consisting of a primary or secondary 17, and a secondary or primary 18. Connected to 18 I have shown three taps 19, 20 and 21, which are connected respectively to ring 12, ring 7 and central rod 3¹. Terminal 22 is the other end-terminal of winding 18. It will be obvious that when connections are made to disks 4, 4¹ or 4², that different voltages may be obtained from winding 18.

Referring now to Figs. 4 and 5, I have shown the special form of connector which I

use in conjunction with the terminal for readily obtaining different voltages from winding 18. This connector consists of a conducting member 22, to the end of which 5 is attached a conducting loop 23 adapted to surround members 4, 4¹, etc., and engage with grooves 5. 24 is a sleeve which fits loosely over an end of loop 23, and is adapted by its movement to tighten loop 23 in 10 grooves 5 in a manner which will be well understood. Fastened to conductor 22 is shown a member 25 having a screw-thread, and in engagement with this screw-thread is a nut 26, which may be turned on member 15 25, and thus moved toward or away from loop 23. Such operation will move sleeve 24, tighten loop 23, and hold the sleeve in a fixed position when the loop is so tightened. Conductor 22 may be insulated in a well known 20 manner, but I have shown it insulated by members 27 which encircle it, and consist of beads of a heat-refractory substance, such as porcelain, glass, etc.

The operation of my invention will be 25 readily understood. If it is desired to make connection with tap 19, for example, nut 26 is unscrewed, so that sleeve 24 permits loop 23 to be as loose as possible. The loop is then slipped over the various disks until it is 30 brought in contact with disk 4² and placed in the groove surrounding the edge of said disk. Nut 26 is then screwed up so that sleeve 24 tightens the loop 23 about groove 5. If it is desired to make connection with any 35 other tap, a similar course of procedure may be adopted.

While I have shown members 4 as substantially circular and disk-like in character, it is obvious that they may be made in other 40 shapes, and a corresponding change made in the shape of loop 23, as will be well understood by those skilled in the art. It will also be obvious to those skilled in the art that while I have shown the conducting members 45 8, 14, etc., and members 7, 9, etc., as being made in the form which I have found most advantageous for the carrying out of my invention, they may be made in many well-known manners without departing from the 50 spirit of my invention.

While I have described a preferred embodiment of my invention, I do not limit myself to this embodiment but seek in the appended claims to cover all embodiments 55 which will be obvious to those skilled in the art and will not depart from the spirit of my invention.

What I claim as new and desire to secure by Letters Patent of the United States, is,—

1. A compound terminal composed of a 60 central member, pairs of conducting rings of varying diameters surrounding the member adjacent its ends and insulated from it, conductors joining rings of like diameter insulated from each other, the lower rings uninsulated as to their exteriors, the upper rings each attached to a conducting disk, said disks being substantially coaxial with and surrounding the central member, and insulating members insulating the disks from each 65 other and from the central member.

2. A compound terminal composed of a central rod of conducting material, pairs of 70 conducting rings of varying diameters surrounding the rod adjacent its ends and insulated from the rod, conductors joining rings of like diameter insulated from each other, the lower rings uninsulated as to their exteriors, the upper rings and the central rod each attached to a conducting disk, said 75 disks being substantially coaxial with and surrounding the central rod, and insulating members insulating the disks from each other and from the central rod.

3. In combination, a compound terminal 80 composed of a plurality of conductors attached to a plurality of substantially circular coaxial conducting members insulated from each other as to their interior surfaces, and a connector having a looped end adapted to inclose said members and means for tightening the said loop on said members.

4. In combination, a terminal composed of a conductor terminating in a substantially disk-shaped conducting member, and a connector having a looped end adapted to encircle said disk and a nut on the connector adapted to tighten said loop on the disk.

5. In combination, a terminal composed of a conductor terminating in a substantially 95 disk-shaped conducting member having a groove about its edge, a conductor having a looped end adapted to engage said groove, a movable sleeve adapted by its movement to tighten said loop in said groove, and a nut 100 adapted to move said sleeve and hold it in a 105 fixed position.

In witness whereof, I have hereunto set my hand this twenty-sixth day of May 1909.

EARLE G. WINSTON.
